UNITED STATES PATENT OFFICE.

HENRY ALBERT BROWN, OF HUNTINGTON, WEST VIRGINIA, ASSIGNOR TO HOMER
BALLENGEE, OF RHODHISS, NORTH CAROLINA.

ADVERTISING DEVICE.

Application filed May 6, 1926. Serial No. 107,244.

This invention relates to advertising apparatus, one of its objects being to provide a structure containing shiftable panels carrying advertising matter, continuously operating means being provided for shifting the panels successively to display positions, each panel being brought ultimately into display position at each side of the housing in which the panels are located.

10 A further object is to provide a structure of this character which is simple and efficient, which can be cheaply manufactured, and which is durable and compact in construction.

15 With the foregoing and other objects in view which will appear as the description proceeds, the invention resides in the combination and arrangement of parts and in the details of construction hereinafter described and claimed, it being understood that changes in the precise embodiment of the invention can be made within the scope of what is claimed without departing from the spirit of the invention.

20 In the accompanying drawings the preferred form of the invention has been shown.

In said drawings:—

Figure 1 is a front elevation of the device.

Figure 2 is a section on line 2—2, Figure 1.

30 Figure 3 is a similar view with the panels removed, the conveyor being indicated by full and dotted lines.

Figure 4 is a section on line 4—4, Figure 2.

Figure 5 is a perspective view of a portion of the conveyor.

35 Referring to the figures by characters of reference 1 designates a hollow base having an elongated housing 2 upstanding therefrom, this housing being provided at one end within opposed sides with windows 3 and 4 respectively through which the shiftable signs are adapted to be displayed. The remaining spaces upon the front and back walls of the housing can be occupied by permanent signs as shown at 5.

40 Arranged transversely of the housing 2 at the center thereof and between the permanent signs and the windows is a partition 6 which is spaced from the front and back walls of the housing. A horizontal parti-

tion 7 is arranged within the base 1 and constitutes the floor of the housing 2, this horizontal partition having a continuous slot 8 extending close to the sides of the housing. That portion of the slot adjacent one of the permanent signs 5 is arranged close to the back of the sign as indicated at 8^a and merges, at the adjacent sides of the partition 6, through an obliquely disposed slot portion 8^b, into a straight slot portion 8^c which is arranged back of but is spaced inwardly from the window 4. The slot portions 8^a and 8^c merge into semi-circular portions 8^d which in turn merge into slot portions 8^e and 8^f which communicate, at one side of the partition 6, through an obliquely disposed slot portion 8^g. The slot portion 8^f is located close to the window 3, while the slot portion 8^e is spaced inwardly from the permanent sign in line with said window 3. Thus it will be seen that the distance between the slot portions 8^a and 8^c is the same as the distance between the slot portions 8^e and 8^f. Series of anti-friction balls 9 are arranged upon the floor of the horizontal partition between the opposed portions of the slots. That portion of the horizontal partition bounded by the slots may be fixedly supported in any suitable manner, as by means of posts 10 and sprockets 11 may be journaled on these posts, these sprockets engaging an endless chain 12. Secured to one of the links of the chain is a crank arm 13 mounted for rotation relative to the link and having an upstanding finger which projects through the slot 8.

45 Secured to the inner surface of the housing 2 above and below the window 4 are springs 14 and similar springs 15 are secured to the inner surface of the opposite wall of the housing at points adjacent the upper and lower portions of the permanent sign 5 carried by said wall.

The partition 6 divides the interior of the housing into two compartments 16 and 17 respectively. Housed within each of these compartments is a series of frames 18, each frame carrying a panel 19 the two faces of which are exposed within the frame, faces carrying any suitable advertising matter or

the like. By providing these frames which practically fill the two compartments and by providing springs 14, it will be apparent that the compartment 16 will have one frame 5 therein constantly pressed toward and close to the window 3 while the springs 14 will thrust the frames in said chamber away from the window 4. Thus the frame nearest the window 3 will be located directly 10 above the portion 8^f of the slot. The frames in the compartment 17 will be pressed in the opposite direction, one frame being pressed against the permanent sign 5 adjacent window 4 so as to be located above the portion 15 8^a of the slot while the opposite frame in said compartment will be pressed away from the other permanent sign. It will be noted that the portion 8^b of the slot is normally positioned below the space between 20 two of the panels in compartment 16 while the portion 8^e of the slot is normally located between two of the panels in the compartment 17.

The chain or conveyor 12 may be driven in 25 any suitable manner, as by means of a motor, not shown, and which may be housed in the base 1. Assuming that the chain is traveling in the direction indicated by the arrow in Figure 3, then the crank arm 13, 30 which is projecting upwardly through the slot 8 will travel into the portion 8^f of the slot and come against the end of the frame 18 nearest the window 3. This frame will thus be thrust longitudinally out of position 35 back of the window and will be wedged in the chamber 17 between the permanent sign 5 nearest window 3 and the frame adjacent said permanent sign. This addition of a frame to the chamber 17 is permitted by the springs 15. As the frame is drawn from the compartment 16 the springs 14 and 15 in said compartments will readjust the frames so that they will lie compactly in the compartments. As the shifted 40 frame is brought to position in the compartment 17, the crank arm 13 will be deflected laterally by the diagonally disposed portion 8^g and will thus come into the portion 8^e of the slot so that the crank arm will become disengaged from the frame and will 45 be free to travel along the compartment 17 and around into the portion 8^a of the slot where it will engage one end of the first frame in the compartment 17 and thrust said frame longitudinally into the compartment 16 and back of the window 4. As soon 50 as the frame is thus shifted into position back of the window 4, the crank arm will be deflected inwardly by the diagonal portion 8^b of the slot, whereupon the crank arm will travel longitudinally along the bottom of the compartment 16 until it comes against the next frame located back of the window 3, whereupon the foregoing operation will be 55 repeated. Thus it will be seen that the

signs will be constantly changing, each sign being brought successively to position back of the window 3 and also back of the window 4.

Although in Figure 2 certain of the 70 frames have been shown directly above the portions 8^c and 8^d of the slot, it will be understood that as soon as an additional frame is forced into either of the compartments 16 or 17, the said frame or frames 75 will be thrust inwardly so as to leave said portion or portions of the slot exposed, thus to allow the free passage of the crank arm 13 therealong. By providing the anti-friction devices 9, the frames can be shifted 80 longitudinally or laterally without producing undesirable friction.

It is to be understood of course that if desired the permanent sign 5 can be removed, thus leaving an open window 85 corresponding with the window 3 through which the movable signs will be successively displayed. As the springs 15 are not attached to the back of the sign 5 but are merely secured above and below said sign, 90 the removal of this sign will not affect the said springs 5.

Obviously instead of using chains and sprockets as shown and described, belts and pulleys may be employed. The modification is so obvious that it is not deemed necessary to illustrate the same.

What is claimed is:

The combination with a base, of a housing thereabove having separate compartments, there being openings at opposite sides of one of the compartments, of a group of frames mounted on edge within each compartment, springs upon one wall of one compartment and the opposed wall of the other 100 compartment for pressing the frames against those walls of the compartment remote from the springs therein, an endless conveyor chain within the base extending throughout the length of the housing thereabove, a crank arm carried by and extending upwardly from one of the pivots of the chain and mounted for rotation relative to the chain, there being an endless slot in the top of the base above the chain and extending beyond the sides of the housing, said slot having opposed parallel portions extending longitudinally of the housing and base, those portions of the slot adjacent the center of the housing being offset along parallel lines, said slot constituting a guide for the crank arm during the movement of the chain in one direction, thereby to direct the crank arm against the back edge of one frame in one of the compartments, and 110 thrust the frame along the bottom of said compartment into the space behind the frames in the next compartment, the springs in said compartment constituting means for shifting said frame out of the path of the 115

120

125

130

next frame to be inserted into said compartment, said slot constituting means for successively guiding the crank arm out of engagement with the last inserted frame and 5 into engagement with the back edge of another frame in the last named compartment thereby to thrust said engaged frame into

the space back of the group of frames from which the first frame was removed.

In testimony that I claim the foregoing 10 as my own, I have hereto affixed my signature.

HENRY ALBERT BROWN.
